REGINALD W. BIRD, OF BROOKLINE, MASSACHUSETTS, ASSIGNOR TO FLINTKOTE MANUFACTURING COMPANY, OF RUTHERFORD, NEW JERSEY, A CORPORATION OF NEW JERSEY.

ROOFING-STRIP.

1,130,368.

Specification of Letters Patent. Patented Mar. 2, 1915.

Application filed February 5, 1912. Serial No. 675,650.

To all whom it may concern:

Be it known that I, REGINALD W. BIRD, a citizen of the United States, and resident of Brookline, in the county of Norfolk and 5 State of Massachusetts, have invented certain new and useful Improvements in Roofing-Strips, of which the following is a specification.

This invention relates to roofing made of 10 flexible sheet material.

One feature of the invention lies in the formation of a blank of sheet material which is divided into a plurality of roofing strips.

The terms "roofing material" and "roofing strip" as used throughout this specification are not intended to have any limiting effect upon the adaptation of the invention to any one specific part of a supporting structure, the article hereinafter described 20 being adapted for use upon walls as well as upon roofs.

The blank of sheet material from which the roofing strips are produced has continuous longitudinal marginal portions, a plurality of series of narrow slots, each series extending longitudinally and each slot extending transversely, and a straight longitudinal continuous portion between the slots of one series and the slots of another series, 30 The purpose in providing the slots is to render the roofing strips capable of simulating shingles, and the purpose of forming the blank so that its longitudinal margins are continuous is to facilitate handling the material and rolling it for shipment, and for avoiding the liability of breaking or otherwise injuring the portions which simulate shingles. The purpose in forming the blank with a longitudinal continuous portion be- 35 tween the slots of one series and the slots of an adjacent series is to make it possible to divide the blank along a longitudinal straight line between two series of slots without intersecting any of the slots.

Each roofing strip, when ready for laying, has a series of slots which are relatively near the edge which is exposed when the strips are laid upon a foundation in overlapping relation. The exposed marginal portion of each strip when laid is continuous, because of the fact that the slots do 45

not extend to the edge. Each tab which represents a shingle is connected by integral parts of the strip with the two adjacent tabs, the connecting portions being left for 55 the purpose of better holding the lower ends of the tabs.

In order to carry out the simulation of shingles as far as possible, the continuous marginal portion along the lower edge of 60 each strip is turned back, thus increasing the aggregate thickness at the lower edge of each tab. The line along which the turned-back portion is bent would preferably intersect the slots which define the shingle-like 65 tabs, because such formation gives the slots the appearance of being open at the lower ends, the turned-back portion being preferably turned under rather than over so that the marginal portion which is turned back 70 will be concealed with the exception of the narrow portions connecting the ends of the tabs. These connecting portions, however, being removed from the plane of the outer surface, are scarcely noticeable, and the 75 simulation of shingles is carried to an advanced condition, while at the same time the lower ends of the tabs are left connected with each other so that they reinforce each other and preserve uniform spaces between 80 them.

Of the accompanying drawings which illustrate the invention: Figure 1 represents a portion of a blank of flexible sheet material suitable for roofing purposes, which 85 blank is of indeterminate length. Fig. 2 represents a portion of a roofing strip, on a somewhat larger scale, which strip is the result of dividing into two pieces the blank shown by Fig. 1. Fig. 3 represents a view 90 from the outer side of the strip after its lower marginal portion has been turned under. Fig. 4 represents a section of the strip on a line indicated by 4-4 of Fig. 3. Fig. 5 represents a section of the strip on a line 95 indicated by 5-5 of Fig. 3. Fig. 6 represents an elevation of the inner side of the strip in the condition corresponding to Figs. 3, 4 and 5. Fig. 7 represents an elevation of a roof covering showing the preferred 100 arrangement of the roofing strips when attached to a foundation. Fig. 8 represents

a section indicated by line 8-8 of Fig. 7, showing the preferred relation of the roofing strips and the preferred means for securing the strips to a foundation. Fig. 9 5 represents a smaller section similar to Fig. 8, showing other means for securing the tabs to the foundation.

The same reference characters indicate the same parts wherever they occur.

10 Referring first to Fig. 1, a blank of suitable sheet material is indicated at 15. This blank is made of sufficient width to provide a plurality of roofing strips when it is divided longitudinally. The blank may be 15 made of any desired width, depending upon the number of roofing strips which it is desired to produce from one blank. In the present instance the blank is designed to be divided to produce only two roofing strips. 20 The blank is provided with narrow slots each of which extends transversely of the length of the blank, the slots being arranged in longitudinal series, one of such series being provided for each roofing strip into which 25 the blank is to be divided. Inasmuch as this blank is designed for division into two roofing strips, there are two series of slots. The slots of one series are indicated at 16, and those of the other series are indicated 30 at 16^x. For convenience in preparing the blank, each slot is in line with a slot of the other series; but this relation of the slots is not essential. It is however essential to separate the slots of one series, lat- 35 erally with relation to the length of the blank, from the slots of the other series by a straight continuous portion of the blank extending longitudinally. The longitudinal marginal portions of the blank in- 40 dicated at 18 and 18^x are likewise continuous, the ends of all the slots being closed by the three longitudinal continuous portions above described. The provision of the intermediate portion makes it possible to 45 divide the blank along a straight longitudinal line, as for example the line indicated at 17, without intersecting any of the slots. The blank, when so divided, provides two roofing strips of similar formation, each of 50 which strips has a series of slots whose ends are all closed, which slots define tabs 19 re- sembling shingles except that their lower ends are connected with each other by narrow connecting portions 19^x. By terminat- 55 ing the slots within the edges of the strip, each strip is provided with two continuous longitudinal marginal portions.

Each strip is intended to be creased or folded along a longitudinal line, as at 20, 60 which line preferably intersects the slots near their lower ends. The blank may, if desired, be scored to define the line 20 before the blank is divided into strips. The strip whose lower marginal portion is folded back

on the line 20 will have the appearance 65 shown by Figs. 3 to 6. The marginal portion is preferably folded under rather than over in order that it may be almost entirely concealed when the strips are secured to a foundation as hereinafter explained. One 70 effect of folding back the marginal portion is to increase the aggregate thickness along the lower edge, the thickness thereby effected being more nearly equal to the thickness of the exposed lower end of the usual tile or 75 wooden shingle. Another effect of turning back the marginal portion is to make it appear as if the lower ends of the slots 16 were open and as if the lower ends of the tabs 19 were free and disconnected from each other. 80 In reality, however, the ends of the slots are not opened and the tabs are not disconnected from each other. The connecting portions 19^x are scarcely noticeable when the strip is attached to a foundation, but they are as 85 effective as before the folding operation in maintaining uniform distance between the lower ends of the tabs and in reinforcing the tabs.

When the roofing strips such as that above 90 described are laid upon and secured to a suitable foundation, they are preferably arranged in the relation shown by Figs. 7 and 8. A foundation is indicated at 21. The first roofing strip attached thereto is secured 95 at the lower edge of the foundation, and the succeeding courses of strips are secured at successively higher positions, in accordance with the usual manner of shingling, the lower edge of each strip lapping over the 100 strip below it. Each strip upon being laid against the foundation is secured thereto by nails 22 driven through the upper marginal portion 18, preferably near the upper edge. The strips, as shown by Fig. 8, are 105 overlapped to such extent that the lower ends of the tabs of one strip are slightly below the upper edge of the second strip below, thus providing no less than two layers of roofing material at all parts and 110 three layers at some parts. The portions which are folded under increase the number of layers to four at the points where the turned-under portions lie.

After the requisite number of roofing 115 strips for the entire supporting surface have been secured thereto by nails 22, the tabs 19 may be fastened by suitable fasteners 23, one of which may be driven through each tab. The fasteners 23 shown in Fig. 8 are 120 bifurcated at their inner ends and are turned back and clenched against the inner side of the second layer from the foundation. The outer ends of the fasteners have heads. Each fastener is driven through the 125 doubled portion of a tab and through the marginal portion 18 of the strip below, and clenched against the inner side of said strip

below instead of being driven through the second strip below. The purpose in thus clenching each fastener is to avoid penetrating the layer which is in contact with the foundation, thus avoiding a passage through which moisture might penetrate to the supporting structure 21. Whatever moisture does penetrate through the opening formed by the fastener 23 will gravitate down upon the exterior of the layer next below and be thus conducted out into the open atmosphere instead of being conducted into the supporting foundation.

When the lower end of each tab is secured in the manner explained, its outer layer is held directly by the head of the fastener. Each tab is therefore held not only by its own fastener but by the portions 19 which connect it with the adjacent tabs, the reinforcement thus provided adding greatly to the stability of the tabs in resisting the lifting force of a strong wind.

The method employed for clenching the fasteners 23 in the manner explained does not form any part of the present invention, but it may be briefly described. The fasteners 23 are inserted in the uppermost strip first. Before a fastener is driven, a thin metal plate is inserted temporarily between the second and third strips from the top and is placed in such position as to be in line with the fastener which is being driven. The metal plate is removed as soon as the fastener is driven and clenched and is placed in the same relation to another tab, and another fastener is driven in the same manner. When all the tabs have been secured in this manner, the roofing strips are all connected with each other so as to form a roofing unit, the unit being otherwise secured to the supporting foundation as hereinbefore explained.

Each tab may be fastened down by a nail such as that indicated at 24 in Fig. 29, instead of by the fastener 23 above explained. The nail 24, as shown, is driven through both layers of the tab and through the two strips therebeneath and into the supporting structure 21. A fastener of this kind, driven in this way, is fully as effective as a fastener 23 for securing the tab, but is not as desirable because moisture may seep through the several layers of material, each of which is penetrated, and ultimately lodge in the supporting foundation.

Having thus explained the nature of my said invention and described a way of constructing and using the same, although with-

out attempting to set forth all the forms in which it may be made or all the modes of 60 its use, what I claim is:

1. A roofing strip composed of flexible sheet material and having a series of narrow slots of which each extends transversely of the length of the strip, said series extending longitudinally of the strip, the strip having two continuous longitudinal marginal portions, and a longitudinal bend, the marginal portion on one side of said bend lying against that on the other side and 65 crossing below said slots, whereby the aggregate thickness is increased, said bend intersecting said slots, whereby the slots are made to appear to be open at the ends.

2. A roof covering comprising overlapping strips of flexible sheet material, each strip having along its exposed edge a series of tabs, the strip having a straight continuous narrow marginal portion along said edge connecting the outer ends of said tabs. 75

3. A roofing covering comprising overlapping strips of flexible sheet material, each strip having along its exposed edge a series of tabs, the outer ends of said tabs being folded under, said strip having a 85 straight continuous narrow marginal portion connecting the folded-under ends of the tabs and exposed by the slots between the tabs.

4. The combination with a supporting surface, of a plurality of overlapping strips of sheet material, each strip having along its exposed edge a series of tabs of which the extremities are folded under, the strip having a straight continuous marginal portion 95 connecting the folded-under extremities, fasteners extending through both layers of the doubled portions of the tabs, and through the strip next below, and anchoring fasteners extending through the upper 100 portion of each strip and into said supporting surface, said anchoring fasteners being concealed by the strip next above.

5. A roof covering comprising overlapping strips of flexible sheet material, each 105 strip having a series of exposed tabs extending downwardly, and having straight portions connecting said tabs below their upper ends and exposed by the slots which form the tabs.

In testimony whereof I have affixed my signature, in presence of two witnesses.
